FIG. 1

FIG. 3

FIG. 4

FIG. 2

FIG. 5

FIG. 6

FIG. 7

FIG. 1 is a front elevational view of a bottle or similar article embodying our new design;

FIG. 2 is a front elevational view of a modified form thereof;

FIG. 3 is a top plan view thereof;

FIG. 4 is a bottom plan view of FIG. 2;

FIG. 5 is a front elevational view of another modified form thereof;

FIG. 6 is a perspective view of the bottle of FIG. 1; and

FIG. 7 is a bottom plan view of the bottles in FIGS. 1, 5 and 6.

The sides opposite those shown in the elevational views are the same in appearance as the respective sides shown.

The dominant features of our design reside in the portions shown in full lines.

We claim:

The ornamental design for a bottle or similar article, as shown and described.
